Attorney

UNITED STATES PATENT OFFICE.

HENRY A. AMMANN, OF SPOKANE, WASHINGTON.

INDIVIDUAL-TOWEL DEVICE.

1,172,245.

Specification of Letters Patent. Patented Feb. 22, 1916.

Application filed December 2, 1915. Serial No. 64,715.

To all whom it may concern:

Be it known that I, HENRY A. AMMANN, a citizen of the United States, residing at Spokane, in the county of Spokane and State of Washington, have invented certain new and useful Improvements in Individual-Towel Devices, of which the following is a specification.

This invention relates to improvements in individual towel devices of that character in which provision is made for holding the towels on a retainer so that the towels can be withdrawn from the stack by the user and advanced on the retainer to a suitable point of use.

It is one of the objects of this invention to provide means for supporting the towels on edge, that is, with the sides of the towels substantially vertically disposed, a retainer being extended through the stack of clean towels in upright or edge position for withdrawal of the towels from the stack along the retainer.

In the most preferred form of my invention, the towels are supported by subjacent engagement of the support with the lowermost edges of the towels and the retainer or stringer is flexible substantially throughout its length, excepting for such attachment as may be necessary to anchor the retainer at its end or ends.

A further feature of the invention consists in the provision of follower means for engagement with the foremost towel of the clean stack for supporting the towels in orderly form as the stack is decreased in volume by withdrawal of towels. This feature of my invention is serviceable and highly advantageous in certain embodiments where retainers are not used.

Other features and objects of the invention will be more fully described in connection with the accompanying drawing and will be more particularly pointed out in and by the appended claims.

In the drawing: Figure 1 is a view in front elevation showing one form of my invention. Fig. 2 is a vertical sectional view thereof on line 2-2 of Fig. 1. Fig. 3 is a horizontal sectional view on line 3-3 of Fig. 2.

Like characters of reference designate similar parts throughout the different figures of the drawing.

In the particular form shown, my inven-

tion includes a rack structure or cabinet comprising a back wall 1, side walls 2, a front wall 3, a bottom wall 4 and a shelf 5. The top is shown open and the front wall 3 is of reduced height with respect to the cabinet to provide an opening 6 for ingress of the soiled towels to the lower portion of the cabinet. The construction is so arranged as to provide a receptacle 7 for the soiled towels and a holder or shelf 5, for the clean towels, the receptacle being disposed below the shelf 5, in this particular construction.

In forming the cabinet, I desirably strengthen the same by bending over the edges to form flanges indicated at 8, and above the shelf, the flanges function as stops to prevent excessive outward movement of my improved follower means, which I will now describe.

The towels are indicated at 9, in the form in which they would take when stacked upon the shelf 5, as the clean towels. In this particular form, the shelf 5 is subjacent to the lower edges 10, of the towels 9, and the towels are supported in an upright position with their sides substantially vertical. In order to support the towels in orderly stacked form and at the same time permit of the towels being readily withdrawn one at a time, I employ follower means which includes a follower member 11. The follower member 11 may be in the form of a metal plate or board or any suitable kind of open grilles which presents sufficient area to engage a proportionate face of the foremost towel in order to hold the towels in orderly stacked form. I have herein shown the follower member 11 provided with a central portion 12 which projects upwardly nearest the upper edge 13, of the towels 9, the end portions 14 and 15 being reduced in height with respect to the central portion 12. The reduction at 15, suitably exposes corner portions 16, of the towels 9, so as to make the edge of the foremost towel rest accessible to the user in withdrawing the same.

My improved follower means includes automatic take-up devices which may comprise take-up lines 17, attached to the follower at 18, and extending over eyelets or pulleys 19 and thence downwardly through the shelf 5 where weights 20 are hung upon the lower end of said take-up lines. In practice, I have found that a good grade of cord is very serviceable in a take-up line

inasmuch as the wear on the line is so slight as to be within the tension capacity of a cord of good quality. However, any suitable form of take-up line may be used.

5 My improved device, as now described, is very serviceable in the lavatories of clubs and societies where the members do not wish to be confronted with any form of retaining means for the towels and desire to have them free to be used as a detached towel. Because of the fact that the towels stand on edge, the sides of the towels are fully protected against soot and other dirt and therefore this arrangement affords advantages 10 of sanitary importance. Furthermore, this arrangement enables one to stack the clean towels in such a manner as to always present a foremost towel in a readily accessible position, and at the same time, inclose the 15 end edges of the towels so that the clean stack will present a symmetrical and regular appearance notwithstanding the extent of its decrease. In other words, the lower means takes up any slack so that even 20 the last towel will be supported in an orderly manner.

25

Perhaps the most important advantage of the invention resides in the availability of this form of rack to the use of a retainer, 30 when the rack is disposed in the lavatories of public places where it is desired to prevent patrons from taking individual towels away from the rack.

As illustrated, I provide a towel retainer or stringer 21 which does not extend upwardly from the shelf 5 but which extends through the towels 9, preferably forwardly from the back of the stack in a substantially horizontal position through the 40 stack and outwardly from the foremost towel and thence downwardly or away from the stack dependent upon the location of the receptacle for the soiled towels. This retainer 21 provides for removal of the 45 towels 9 from behind the follower 11, along or lengthwise of the retainer to a position accessible to the desired point of use. In this form of the invention, after the towel has been used, it is allowed to descend by 50 gravity into the receptacle 7, as indicated by the position of towel 22. I prefer to use a retainer or stringer which is in the form of a flexible line and I consider it a feature of my invention to string a flexible line 55 through an edgewise supported stack of clean towels and thence away from said towels, to form a guide for withdrawal of the towels along the stringer. As illustrated, I attach the upper end of the stringer 60 21 to the rack, by any suitable means such as a snap hook and eye 23 and 24 or this end of the wire may be provided with an eye and the snap hook may be fixed to the rack. At any rate detachable connection is 65 desirable. I also prefer to anchor the re-

maining end of the wire and I have shown the same anchored by means indicated at 25 and 26, to the bottom wall 4.

One of the great advantages in using a flexible line, is the availability of these lines or retainers in stringing the towels at the laundry and transporting the clean towels already strung to the place of use so as to avoid stringing operation when the towels are installed on the rack. The only thing necessary is to attach either one or both ends of the flexible line. In the present construction, I prefer to anchor both ends, or at least hold one end so that it will be restrained from absolute freedom of movement.

It is believed that the advantages and utility of my invention will be fully understood from the foregoing description, and while I have herein shown and described one specific form of my invention, I do not wish to be limited thereto except for such limitations as the claims may import.

I claim:—

1. In an individual towel device, a substantially horizontal shelf having a back, for supporting a stack of towels on edge, a weight actuated follower adapted to engage the foremost towel of the stack and adapted to be moved against said towels and toward said back to maintain the towels in stacked edge form and take up the slack of stack reduction in volume without bodily moving the stack, and a flexible stringer extending substantially horizontally through one upper corner of the stack and away from the latter to an accessible point with respect to the user, whereby the foremost towel may be grasped by the user and withdrawn from behind and over the top of said follower and along said stringer to the point of use, substantially as described.

2. In an individual towel device, a shelf having a back for supporting a stack of towels on edge, an actuated follower adapted to engage the foremost towel of the stack and adapted to be moved against said stack and toward said back to maintain the towels in stack form on edge and to take up slack of stack reduction in volume without bodily moving the stack, and a stringer extending substantially horizontally through the stack and away from the latter to an accessible point with respect to the user, whereby the foremost towel may be grasped by the user and withdrawn from behind and over the follower and along said stringer to the point of use, substantially as described.

3. In an individual towel device, means adapted to engage the lower edges and back of a stack of towels to support the latter on edge, a follower, means adapted to move said follower against the foremost towel to

maintain the towels in stack form, and a flexible stringer extending forwardly through said stack and away from the latter to a suitable point of use for withdrawal of the foremost towel of a stack by the user from behind and over said follower and along said stringer to such point of use, substantially as described.

4. In an individual towel device, a shelf and back, an upright follower adapted to be moved along said shelf, means adapted to move said follower along said shelf toward the back, a flexible stringer attached to said back, said stringer being provided with a point whereby towels may be strung upon such stringer, said stringer adapted to be passed through the upper part of said towels as they stand on edge and are held by said follower, and the said stringer being slack over the upper edge of the follower whereby the foremost towel may be withdrawn over the follower and slid along the stringer, substantially as described.

5. In an individual towel device, a shelf and back, an upright follower adapted to be moved along said shelf, means adapted to move said follower along said shelf toward the back, a flexible stringer adapted to be attached to said back, said stringer being provided with a point whereby towels may be strung upon such stringer, said stringer adapted to extend through the upper part of said towels as they stand on edge and are held by said follower, the said stringer being slack over the upper edge of the follower whereby the foremost towel may be withdrawn over the follower and slid along the stringer, and means for securing the forward end of said stringer whereby towels are secured against removal from said stringer, substantially as described.

6. In an individual towel device, means adapted to engage the lower edges of a stack of towels to support the towels on edge and clamp them together, and a flexible stringer adapted to extend substantially horizontally forward through a stack of towels and forward and away therefrom to an accessible point to constitute a suitable

guide for advancing the towels from the stack along said retainer to a point of use, substantially as described.

7. In an individual towel device, means for supporting and clamping a stack of clean towels with their sides substantially vertical, and a flexible stringer adapted to be secured to said supporting and clamping means and adapted to extend forward substantially horizontally through a stack of clean towels and away therefrom to an accessible point, said stringer being slack whereby said flexible stringer will constitute a guide for towels withdrawn from the stack and advanced along the stringer, substantially as described.

8. In an individual towel device, a shelf for supporting a stack of clean towels on edge, an actuated follower engaging the foremost towels to retain the towels upright as the stack is reduced in volume, and a flexible stringer adapted to extend forwardly through a stack of clean towels and away therefrom to an accessible position to form a guide along which the towels may be advanced from the stack to a suitable point of use, and means for securing the forward end of said stringer, substantially as described.

9. In an individual towel device, a shelf for supporting a stack of clean towels in upright edge position, a back and shelf, a follower member adapted to engage the foremost towel of the stack, cords connected with said member and extending along the side edges of the stack and thence downwardly, pulleys over which said cords pass, weights connected with said cords to advance said follower against the stack as the latter is reduced in volume, and a pointed flexible wire secured to said back and adapted to thread a series of towels, said wire being secured at its forward end so that it is in slack relation to said follower, substantially as described.

In testimony whereof I affix my signature.

HENRY A. AMMANN
